UNITED STATES PATENT OFFICE

150,022

DESIGN FOR A CLOTHES DRIER OR SIMILAR ARTICLE

Hercheal Wood Miller, Davenport, Iowa, assignor to American Machine and Metals, Inc., New York, N. Y., a corporation of Delaware

Application March 21, 1946, Serial No. 127,764

Term of patent 7 years

(Cl. D49—1)

To all whom it may concern:

Be it known that I, Hercheal Wood Miller, a citizen of the United States and a resident of Davenport, in the county of Scott and State of Iowa, have invented a new, original, and ornamental Design for a Clothes Drier or Similar Article, of which the following is a specification, reference being to the accompanying drawings, forming part thereof.

Fig. 1 shows a front elevation of a clothes drier or similar article, embodying my new design.

Fig. 2 is a top view of the same clothes drier.

Fig. 3 is a side elevation of the same clothes drier.

I claim:

The ornamental design for a clothes drier or similar article, as shown.

HERCHEAL WOOD MILLER.
